UNITED STATES PATENT OFFICE.

FREDERICK T. BURGESS, OF COVENTRY, ENGLAND, ASSIGNOR OF ONE-HALF TO HUMBER
LIMITED, OF COVENTRY, ENGLAND.

PISTON PARTICULARLY FOR INTERNAL-COMBUSTION ENGINES.

1,226,306.

Specification of Letters Patent.

Patented May 15, 1917.

Application filed October 30, 1916. Serial No. 128,548.

To all whom it may concern:

Be it known that I, FREDERICK TASKER BURGESS, a subject of the King of Great Britain, and resident of Coventry, in the county of Warwick, England, have invented certain new and useful Improvements in Pistons Particularly for Internal-Combustion Engines, of which the following is a specification.

10 This invention relates to pistons particularly for internal combustion engines, and it has for its object to provide an improved construction in which excess of oil passing up the cylinder will be prevented.

15 Usually the lower edge of the piston skirt is thickened so that as the piston descends oil piles up in front of this thickened edge and is forced past the piston skirt and so enters the combustion chamber.

20 According to this invention, this is obviated by beveling the lower edge of the piston, preferably to a knife edge, so that there can be no accumulation of oil as the piston descends, and further I arrange that this

25 beveled part bears outward against the cylinder wall so that it may exert a resilient scraping action, with the result that the oil is scraped off on to the inside of the piston.

30 The accompanying drawing is a side elevation with a part broken away showing one method of applying this invention. The bell mouth of the lower portion of the piston is exaggerated considerably for the sake of clearness.

35 As will be seen, the lower end A of the piston skirt tapers off to a knife edge and it is machined so that the overall diameter of the lower portion of the piston is greater than the diameter at other points. That is to say, the lower end of the skirt is slightly bell-mouthed. The beveling of the end A may be more or less gradual as shown, or not, as required. Consequently this bell mouthed end of the piston exerts a scraping

40 action, and, owing to the beveled edge, as the piston descends, the oil, instead of piling up in front of the descending piston is scraped off on to the inside of the piston.

To provide the lower part A with the required resilience it may be slit vertically or angularly in one or more places as at B, and means are provided for allowing the intermediate parts to spring outward. For ex-

ample these parts may be hammered or peened so as to exert a natural spring outward. Consequently it is possible to make the piston bear the whole way around at its lower edge so that noise is reduced.

The slits may also constitute oil ways allowing a small amount of oil to pass up the outside of the piston and for this purpose they may extend beyond the thin springy edge of the piston. For instance, the piston may be resilient for a distance of say 10 millimeters from the lower edge, and the slots may extend 15 millimeters up the piston, and they may communicate with a recess in the outer surface of the piston if required.

Obviously the springy lower extremity of the skirt may be separate from the main body and be fixed thereto in any suitable way. This might be preferable where the main body is of aluminium or some material which is not suitable for the resilient portion.

By varying the number, length, and direction of the slits A the amount of lubricant allowed to pass from the inside of the piston on to the outer wall can be varied and hence the lubrication of the piston surface can be adjusted.

The result obtained from employing a special scraping ring is quite different from that which is obtained by the present invention. The ring must be cut through at one point to provide resilience, and at this point there is bound to be leakage. Furthermore, as the ring moves upward and downward slightly in the groove as the piston reciprocates the oil is pumped around the back of the ring. By making the special scraping portion integral with the piston there is no difficulty in machining, and it is quite an easy matter to obtain a scraping action which is uniform the whole way around the cylinder.

By this means scraper rings are dispensed with and a simple piston construction obtained which prevents the passage of an excess of oil and also causes the piston to bear evenly the whole way around.

What I claim as my invention, and desire to secure by Letters Patent, is:—

1. A piston having a resilient bell-mouthed lower portion, and a beveled edge

to said bell-mouthed portion, substantially as set forth.

2. A piston having a resilient bell-mouthed lower portion, longitudinal slits in said portion, and a beveled edge to said bell-mouthed portion, substantially as set forth.

In testimony whereof I have signed my

name to this specification in the presence of two subscribing witnesses.

FREDERICK T. BURGESS.
